UNITED STATES PATENT OFFICE.

ELLIOTT J. STODDARD, OF DETROIT, MICHIGAN, ASSIGNOR TO THE H. C. HART MANUFACTURING COMPANY, OF SAME PLACE.

GAS-ENGINE.

SPECIFICATION forming part of Letters Patent No. 533,754, dated February 5, 1895.

Application filed May 31, 1894. Serial No. 513,068. (No model.)

To all whom it may concern:

Be it known that I, ELLIOTT J. STODDARD, of Detroit, in the county of Wayne and State of Michigan, have invented a new and useful 5 Improvement in Gas-Engines, of which the following is a specification.

My invention relates to gas engines, and consists in the improvements hereinafter described and pointed out in the claims.

10 Referring to the accompanying drawing, the figure is a vertical longitudinal section of so much of a gas engine as is necessary to illustrate my invention.

A is a cylinder closed at both ends. B is the 15 piston in said cylinder.

C is the piston rod, D the connecting rod, E the main shaft, and F the fly wheel of the engine.

20 G is a drum concentric with, and immovably connected to the fly wheel F.

H is an arm pivoted upon the shaft E next to the drum G.

The connecting rod D is pivoted at one end to the free end of the arm H.

25 I is a clutch which permits the arm H to turn in a positive direction around the shaft E, independent of the drum G, but prevents any independent turning of said arm with reference to said drum, in the other direction.

30 J is a reservoir for compressed air.

K is a port leading from the reservoir J.

L is a valve covering the port K.

j is a valve case covering the port K and valve L.

35 M is a hand screw passing through the valve case j, and adapted to adjust the tension of a spring m, which spring acts to press the valve L against its seat.

N is a check valve covering a port n which 40 port communicates with the cylinder A, at the opposite end to that with which the port p connects.

Q and R are hand screws by which the tensions of springs q and r may be adjusted, which 45 springs act to press the valves N and P respectively against their seats.

W is a carburetor.

T is a pipe connecting the interior of the valve case j with the port p, and U V w are 50 pipes connecting the interior of said case with the carburetor W and with the port n. A

portion of the compressed air passes through the pipe U and carburetor W, in the latter of which it becomes impregnated with combustible vapor. Another portion of said air passes 55 through the pipe V, and mixes with the portion that has passed through the carburetor W, to form an explosive mixture. The cock in the pipe V is used to vary the size of the passage through said pipe and thus regulate 60 the proportion of air that shall pass through said pipe.

I have not shown nor described the pump by which the supply of compressed air is kept up in the reservoir J, because this is well understood, and forms no part of this invention. For the same reason I have not shown or described the inlet and exhaust valves of the engine.

The operation of the above described device is as follows: Air is compressed by a pump (not shown) and forced into the reservoir J, say at sixty pounds absolute. From the reservoir J the air may pass to the port N through pipes U, w, V, being carbureted 70 and converted into an explosive mixture on its way. From the same reservoir compressed air may pass to the port p through the pipe T. The compressed explosive mixture is admitted behind the piston B, and fired, driving the piston B forward, compressing and storing up the work of said explosion in the air before said piston. On its return stroke, 75 the piston B receives its impulse from the air that has been compressed before it, and gives out the work that has been stored in 80 said air to the main shaft E through the clutch I and drum G. The pressure of the air at the port p, and of the explosive mixture at the port n, is equal to the pressure of 85 the air in the reservoir J, minus the pressure of the spring m. The pressure of the explosive mixture above the valve N, is equal to the pressure below said valve minus the pressure with which said valve is acted upon by the 90 spring q. The pressure of the air above the valve P is equal to the pressure below said valve minus the pressure of the spring r.

Now, if the fill chamber and the space in front of the piston B are so proportioned that the piston B makes a stroke of the required length 100 under the impulse of the explosion, the work

the engine is able to do may be increased or diminished by turning the hand screw M, thus increasing or diminishing the pressure in both ends of the cylinder A to the same amount, and the length of the stroke will not be greatly altered, inasmuch as the resistance to the forward movement of the piston is increased or diminished as the impelling force is increased or diminished.

10 Should it be desirable to alter the length of the stroke the pressures in the two ends of cylinder A may be separately adjusted by the hand screws Q R.

15 What I claim as my invention, and desire to secure by Letters Patent, is—

1. The combination with a gas engine in which the energy of the explosion is stored up in a spring, of means adapted to vary the amount of explosive charge and strength of 20 said spring in the same proportions, substantially as shown and described.

2. The combination with a gas-engine in which the energy of the explosion is stored up in a spring, of means adapted to vary the amount of the explosive charge and the strength of said spring in varying proportions, 25 substantially as shown and described.

3. In a gas-engine, the combination of a cylinder A closed at both ends, a reservoir J of 30 compressed gas, a pipe U V communicating with the cylinder A at one end, a pipe T communicating with said cylinder at the end of said cylinder opposite to that with which the

35 pipes U V communicate, a valve L adapted to close the passage way between said reservoir and the pipes U, V, T, the spring m, acting to press said valve upon its seat against the pressure of the air in said reservoir, and means for adjusting the tension of said spring.

4. In a gas engine the combination of a cylinder A, closed at both ends, a reservoir of 40 compressed gas J, pipes U, V and T communicating with opposite ends of said cylinder, and with said reservoir, a valve N or P in each of said pipes, a spring q or r, acting to 45 close said valve against the pressure of said gas, and means for adjusting the tension of said spring, substantially as shown and described.

5. In a gas engine the combination of a cylinder A, closed at both ends, a reservoir of 50 compressed gas J, pipes U, V and T, communicating with opposite ends of said cylinder and with said reservoir, a valve N or P in each of said pipes, a spring q or r acting to 55 close said valve against the pressure of said gas, means for adjusting the tension of said spring, a valve L in the passage way between both of said pipes and the reservoir J, a spring m acting to close the valve L against the 60 pressure of spring m, substantially as shown and described.

ELLIOTT J. STODDARD.
